UNITED STATES PATENT OFFICE

2,200,194

AUTOPOLISHER

James Dorsey Thompson, West Medford, Mass.

Application October 13, 1939, Serial No. 299,373

5 Claims. (Cl. 51—170)

This invention relates to a sanding and polishing machine, the primary object of the invention being to provide a machine of this character having a movable plate or shoe over which the sanding or polishing cloth is stretched, the machine being of the portable type so that it may be conveniently held in the hand of the operator and readily moved over the surface under treatment.

10 An important object of the invention is to provide a portable pneumatic machine for sanding and polishing surfaces, wherein the shoe or plate supporting the sanding or polishing cloth, is rapidly reciprocated to accomplish the sanding or polishing result.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention:

Referring to the drawings:

Figure 1 is a plan view of a sanding and polishing machine constructed in accordance with the invention, a portion of the cover thereof having been removed illustrating the inner structure.

Figure 2 is a sectional view taken on line 2—2 of Figure 1.

Figure 3 is a vertical sectional view taken on line 3—3 of Figure 2.

Figure 4 is a sectional view taken on line 4—4 of Figure 2.

Figure 5 is a sectional view taken on line 5—5 of Figure 3.

Figure 6 is a sectional view taken on line 6—6 of Figure 2.

Referring to the drawings in detail, the body portion of the device is indicated generally by the reference character 5, and as shown by Figure 3 of the drawings, comprises a main central portion 6 bored to provide a cylinder 7, the base of the body portion being wide and extended throughout the entire length thereof, providing a supporting surface 8 over which the shoe or plate that supports the sanding or polishing cloth, operates.

The shoe or plate supporting the sanding or polishing cloth, is indicated by the reference 9, and as shown, is appreciably longer than the supporting surface 8, so that one end thereof will extend beyond the supporting surface, pro-

viding a substantially long and wide sanding or buffing surface.

The edges of the shoe or plate 9 extend upwardly as at 10 and overlie the longitudinal edges of the supporting surface 8, so that the shoe or plate 9 may reciprocate freely over the supporting surface.

The reference character 11 designates the piston rod of the machine, that carries the piston 12 which is mounted intermediate the ends of the rod 11. The ends of the rod 11 extend through the removable heads 13, which are packed as at 14 to insure a close fit between the rod 11 and heads. The ends of the shoe or plate 9 extend upwardly as at 15, and since the shoe or plate 9 is constructed preferably of yieldable sheet metal, these upturned ends provide clamps for clamping the sanding or polishing cloth to the shoe or plate. Blocks indicated at 16 bear against the upwardly extended ends 15 of the shoe or plate 9, and are provided with threaded openings to receive the threaded ends of the piston rod 11.

The sanding or polishing cloth in the present showing, is indicated by the reference character 17 and is shown as having one of its ends extended over the upwardly extended end of the shoe or plate 9 and clamped between the block 16 and upstanding end of the shoe or plate, securing the sanding or polishing cloth in position at this end of the machine. The opposite end of the sanding or polishing cloth 17 is wound on the roller 18 and passes downwardly through the wax container 19, from where it is stretched over the outer surface of the shoe or plate 9. Thus it will be seen that due to this construction, wax may be readily applied to the surface under treatment.

The wax container 19 is removably held in position by means of the spring arms 20 so that it may be readily and easily disconnected from the machine, when the machine is to be used in sandpapering, and a strip of sanding cloth is stretched over the shoe or plate 9. When a strip of sanding cloth is used, both ends of the sanding cloth are clamped between the blocks 16 and upturned ends of the shoe or plate 9.

The body portion 5 is provided with lateral passageways 21 and 22 which communicate with the cylinder 7, at the ends thereof, the inner end of the passageway 21 being extended upwardly, the passageway terminating at the upper edge of the body portion.

The passageway 22 also extends towards the center of the body portion and has its inner end

disposed upwardly terminating at the upper edge of the body portion.

Disposed between the upwardly extended ends of the passageways 21 and 22, is a passageway 23 providing the exhaust passage of the machine.

The handle of the machine is indicated by the reference character 24 and is in the form of a casting adapted to be bolted onto the upper surface of the body portion, as shown by Figure 1 of the drawings. The handle section 24 is provided with a central hollowed-out portion providing a housing for the movable valve member 25 which is shown as mounted therein, the valve member 25 being secured to the vertical shaft 26, to which the arm 27 is secured. This arm 27 is of a length to extend downwardly over the side of the body portion, the right angled end 28 thereof being disposed directly over the control rod 29 mounted in suitable bearings formed in the body portion, and having connection with the ends of the shoe or plate 9. Adjustably mounted on the control rod 29, are nuts 30 that are adapted to engage the lug 31 extending downwardly from the right angled end 28 of the arm 27, so that as the control rod 29 reciprocates, the arm 27 will be operated accordingly, moving the valve 25, for purposes to be hereinafter more fully described.

The valve 25 is formed with a curved bore 32 which is adapted to register with one end of either the bore 21 or 22, and the exhaust passageway 23. It will be obvious that when the valve member is moved to one of its positions to exhaust air from one side of the piston, the air will be entering the opposite bore to move the piston in the opposite direction.

The bore 33 formed in the handle section of the machine, constitutes the intake bore or passageway through which the compressed air enters the machine, from the hose 34 which may be connected with any suitable compressed air supply. Mounted in the handle of the machine at a point adjacent to the intake end of the bore 33, is a valve 35 the stem 36 of which extends inwardly directly under the grip 37 of the handle. This valve is of a construction to open under the pressure of the air entering through the hose 34. A lever indicated at 38 has pivotal connection with the handle and has one of its ends disposed adjacent to the free end of the rod 36 so that as the lever is moved inwardly to the position shown in full lines in Figure 6 of the drawings, the valve will be moved to its closed position, or to a position to cut off the flow of compressed air into the cylinder. When the lever is released by the operator, the valve will be moved to its open position, and the compressed air may flow into the cylinder to operate the piston 12.

Thus it will be seen that due to this construction, the action of the piston 12 to accomplish the operation of the shoe or plate 9, may be controlled at the will of the operator.

What is claimed is:

1. A device of the class described, comprising a body portion, a horizontal cylinder formed in the body portion, and having a wide supporting surface, a shoe slidably mounted on said supporting surface, a piston rod operating through the cylinder, a piston mounted intermediate the ends of said rod and disposed within the cylinder, clamping means at the end of the rod for clamping a surface treating cloth thereto, and means for

directing air to the cylinder alternately at opposite sides of the piston for reciprocating the piston and shoe.

2. A device of the class described comprising a body portion, a horizontal cylinder formed in the body portion and having a wide supporting surface, a shoe slidably mounted on said supporting surface, a piston rod operating through the cylinder, a piston disposed intermediate the ends of the rod and operating within the cylinder, means for directing air alternately to opposite sides of the piston for reciprocating the piston and piston rod, a reciprocating shoe mounted on the supporting surface, a clamp at each end of said shoe for clamping a surface treating cloth to the shoe, and a valve for controlling the passage of air under pressure to the cylinder.

3. A device of the class described comprising a body portion, a horizontal cylinder formed in the body portion and having a wide supporting surface, lateral passageways extended along the sides of the cylinder and having their outer ends communicating with the cylinder, the opposite ends of the passageways being open, said body portion having an exhaust opening, a movable valve member having an opening adapted to establish communication between one end of one of the passageways and the exhaust opening at each movement of the valve member, a valve housing in which the valve member is mounted, said valve housing having an opening through which air enters, said valve adapted to operate to control the passage of air to opposite sides of the piston alternately for reciprocating the piston, a reciprocating shoe mounted on the wide supporting surface, and a surface treating cloth mounted on the shoe and movable with said shoe.

4. A device of the class described comprising a body portion, a horizontal cylinder formed in the body portion, said body portion having a wide supporting surface, a shoe slidably mounted on the supporting surface, a piston mounted intermediate the ends of said rod and operating in the cylinder, blocks secured to the ends of the piston rod, the shoe having upturned resilient ends, blocks secured to the ends of the piston rod and adapted to clamp a surface treating cloth against said upturned ends of the shoe, a valve for controlling the passage of air to said cylinder, and means for operating said valve to control the passage of air to opposite sides of the piston alternately, and a manually controlled valve for controlling the passage of air to the first mentioned valve.

5. A device of the class described comprising a body portion, a horizontal cylinder formed in the body portion and having a wide supporting surface, a shoe slidably mounted over said supporting surface, a piston rod extending through the cylinder, a piston mounted intermediate the ends of the rod, means at the ends of the shoe for securing a surface treating cloth to the shoe, a container at one end of the shoe adapted to contain floor coating liquid, said container adapted to deposit the floor treating liquid to the surface under treatment, and means controlled by the action of the piston for controlling the passage of air alternately to opposite sides of the piston for reciprocating the shoe and surface treating cloth mounted thereon.

JAMES DORSEY THOMPSON.
